UNITED STATES PATENT OFFICE.

EMMIT G. LATTA, OF FRIENDSHIP, NEW YORK, ASSIGNOR OF TWO-THIRDS
TO ADRIAN C. LATTA, OF SAME PLACE, AND HARVEY D. BLAKESLEE,
OF BUFFALO, NEW YORK.

HAME.

SPECIFICATION forming part of Letters Patent No. 372,377, dated November 1, 1887.

Application filed June 23, 1883. Serial No. 98,994. (No model.)

To all whom it may concern:

Be it known that I, EMMIT G. LATTA, of Friendship, in the county of Allegany and State of New York, have invented a new and 5 useful Improvement in Hames, of which the following is a specification.

This invention relates to an improvement in that class of hames which are composed of a wooden body covered on its inner and outer 10 sides with iron.

The object of the invention is to produce a strong hame at less expense than heretofore, and to improve the means whereby the breast-ring is attached to the hame, and to provide an 15 improved fastening for the lower hame-loop.

My invention consists of the improvements which will be hereinafter fully set forth, and pointed out in the claims.

In the accompanying drawings, Figure 1 20 represents a front elevation of a hame provided with my improvements. Fig. 2 is a vertical section of the hame. Fig. 3 is a sectional elevation of the hame staple and breast-ring attachment in line *xx*, Fig. 2. Fig. 4 is a horizontal section in line *yy*, Fig. 1. Fig. 5 is a side elevation of the breast-ring attachment. Fig. 6 is a side elevation showing a modified construction of the same. Fig. 7 is an elevation of the lower end of the inner hame-iron 25 before it is bent around the lower hame-loop. Figs. 8 and 9 are cross-sections of the hame-irons. Fig. 10 is a view of the lower hame-loop. Figs. 11 and 12 are sectional elevations showing modified constructions of the fastening for the lower hame-loop.

Like letters of reference refer to like parts in the several figures.

A represents the wooden body, which may be of any well-known construction.

40 B represents the outer hame-iron; C, the inner hame-iron; D, the fastening for the upper hame-strap loop; E, the draft-staple; F, the breast-ring; G, the breast-ring attachment, and H the lower hame-loop.

45 The outer hame-iron, B, extends from the lower end of the hame to the upper loop-fastening, D, and the inner iron, C, extends from said fastening over the top of the hame and on the inner side of the latter to the lower end

thereof. The outer iron, B, is made heavier 50 than the inner iron, C, whereby the required strength is obtained at the point of greatest strain with the least amount of iron.

The upper ends of the hame-irons B and C are secured to the hame by the fastening D, 55 which is applied to the outer sides of the ends of the hame-irons, and whose prongs D pass through said ends. Each of the hame-irons is made of uniform thickness from end to end, so that ordinary rolled irons can be applied to 60 the hame without being drawn down by hand, thereby effecting a considerable economy in the hame-covering, as compared with hames in which a heavy iron applied to the outer side of the body is drawn down or made thinner at 65 the ends, where it is welded to a thin iron applied to the inner side of the wooden body.

The hame-irons are rolled with longitudinal grooves *b* on their inner sides, as represented in Figs. 8 and 9, whereby the operation of 70 punching the holes for the fastenings or attachments is facilitated and the greater portion of the material placed in the marginal portions of the bar, where it is not removed by the holes punched through it, thereby forming 75 a very strong and light iron which is easily manipulated in applying it to the wooden body.

The lower end of the inner iron, C, is bent over the lower end of the wooden body to form a shoulder, *c*, and the end is then doubled 80 around the inner bar, *h*, of the lower loop, H. The lower end of the outer iron, B, is doubled around the bent portion of the inner iron, C, and rests against the shoulder *c*, which conceals the end and forms a smooth finish. The 85 bar *h* of the loop H is preferably provided with a tapering lip or spur, *i*, which projects between the doubled portions of the inner iron, C, and serves to hold the loop H nearly rigidly, thereby affording all the advantages of a rigid 90 loop without the expense attending the use of loops forged on the hame-irons.

The lower end of the hame-iron C is preferably provided with openings *d'*, so arranged on the iron that when the end is doubled 95 around the bar *h* of the loop H the openings *d'* will form a space in which the lip or spur *i* is received, and in which the latter has a limited

movement, as it is confined in said space by the bent end of the outer iron, B. The lower ends of the irons C and B are secured together by a rivet, *j*. When the lip *i* is not used, the 5 fastening may be constructed as represented in Fig. 11, in which the lower end of the inner iron, C, is bent to form the shoulder *c* and not doubled around the bar *h* of the loop. If increased strength is required, the end of the 10 inner iron, C, may be extended upwardly on the outer side of the wooden body beyond the rivet *k*, as represented in Fig. 12. This mode of fastening the lower ends of the hame-irons together forms a very neat and strong attachment 15 for the loop H, which latter is thereby prevented from wearing through the bent portion of the outer hame-iron.

The breast-ring attachment is composed of a plate, G, provided on its upper side with a 20 notch, *g*, which straddles the lower leg, *e*, of the hame-staple, and a loop, G', which extends over the edge of the hame and receives the breast-ring E. The hame-staple is provided on its under side with a shoulder, *l*, which 25 bears against the outer side of the plate G. *m* is a prong or pin formed on the inner side of the plate G, and adapted to enter the wooden body A. *n* is an elongated neck formed on the prong *m* adjacent to the plate G, and 30 adapted to enter an elongated hole, *n'*, in the outer hame-iron, B. The notch *g* and elongated neck *n* prevent the attachment from turning on the hame and facilitate repairs when the attachment requires to be renewed.

35 The attachment is secured to the hame by driving the prong *m* into the wood and then securing the draft-staple E to the hame, with its shoulder *l* resting against the upper portion of the plate G, whereby the attachment 40 is firmly secured to the hame. When it is desired to apply a new breast-ring, the attach-

ment is removed by breaking or bending the prong *m*, and the new ring is applied by means of an attachment, *o*, (represented in Fig. 6,) which resembles the attachment G in all respects, except that only the elongated neck *n* of the prong *m* is used, while the portion of the prong *m* which enters the wood is omitted and the attachment secured in place by a wood-screw passing through a hole, *p*. This attachment is readily introduced under the shoulder *l* of the draft-staple, thereby permitting the breast-ring attachment to be renewed and replaced without disturbing the draft-staple. 45

I claim as my invention—

1. In a hame, the combination, with a wooden body and a lower loop, H, of an inner iron, C, having a shoulder, *c*, and an outer iron, B, doubled around the inner bar of the loop and resting with its end against the shoulder *c*, 60 substantially as set forth.

2. The combination, with a loop H, having its inner bar, *h*, provided with a lip or projection, *i*, of a hame-iron having an opening in which said lip has a limited movement, substantially as set forth. 65

3. The combination, with the draft-staple E, provided with a shoulder, *l*, of a breast-ring attachment provided with a plate, G, having a notch, *g*, which embraces a leg of the staple, 70 the shoulder *l* being adapted to bear against the plate G, substantially as set forth.

4. The combination, with the draft-staple, of a breast-ring attachment consisting of a plate, G, having a notch, *g*, and a pin, *m*, provided with an enlarged neck, *n*, substantially as set forth. 75

EMMIT G. LATTA.
